CLAIM

I claim the ornamental design for a low profile case, as shown and described.

DESCRIPTION

FIG. 1 is a top, back left-side perspective of my new design for a low profile case in a joined configuration,
 FIG. 2 is a right-side elevation thereof,
 FIG. 3 is a left-side elevation thereof,
 FIG. 4 is a back-side elevation thereof,
 FIG. 5 is a front-side elevation thereof,
 FIG. 6 is a top plan view thereof; and,
 FIG. 7 is a bottom plan view thereof.

The broken lines in the drawings illustrate portions of the soft bicycle bag that form no part of the claimed design.
